CHARGING AND SWITCHING DEVICE FOR
INTERNAL COMBUSTION ENGINESAuguste Soulet, Lyon, France, assignor to Mag-
netos-France, Lyon, France, a company of
FranceApplication June 7, 1934, Serial No. 729,374
In France July 27, 1933

2 Claims. (Cl. 171—313)

It is known that there exist hand switches intended to short-circuit the lighting dynamo automatic cut-out fitted in vehicles with explosion engines with the object of making the equipment operate without the aid of the battery. Nevertheless these hand switches do not insulate the battery and only short-circuit the automatic cut-out, thus making it necessary to break the circuit of one of the cables of the battery terminals. Another inconvenience is the fact that with a battery charged, if the switch is left in the dynamo position, the battery discharges, when the dynamo is at rest, back through the dynamo.

The hand switch forming the object of the present invention has also the aim of short-circuiting the automatic charging cut-out, but in a quite different way, by completely insulating the battery from the remainder of the installation. In addition this switch is made up in such a way that it at the same time enables the current in the inductors to be switched off and the dynamo to operate on the poles constituted by permanent magnets.

The invention can in any case be well understood with the aid of the supplementary description below and of the attached drawing, which description and drawing are, of course, given above all by way of example.

Figure 1 represents the switch in the battery position.

Figure 2 is a straightened section of this switch in the battery position, through the line 2—2 of Figure 1.

Figure 3 gives the view from below.

Figure 4 represents the switch in the dynamo position.

Figure 5 gives the plan for mounting in a vehicle.

Figure 5a is an obverse view of a switch of Figure 5 showing the rear of two connections upon said switch.

Figure 6 is a modification of the main switch of the invention, illustrating the inclusion of a third or intermediate contact position.

Throughout the views, the same references indicate the same or corresponding parts.

In accordance with the invention the switch A shown in Figures 1 to 5 is a two-way switch.

It is constituted by a plate 1 acting as support for the contact-studs 2, 3, 4, 5, 6, and 7.

A spindle 11 supporting contact strips can turn in the centre of the plate and can make the strips assume the positions X (battery) or Y (dynamo).

One contact strip 8 is riveted to the rotating spindle 11 and can bring into contact the studs

5 and 4 in the position X and the stud 6 and the spindle 11 in the position Y.

Another contact strip 9, riveted to an insulating washer 10, insulated from the spindle 11 and the strip 8, brings into contact in the position X 5 the two studs 2 and 3.

In addition a sunk stud 7 is in permanent contact with the spindle 11 and the strip 8 by means of a brass plate 14.

In the position Y of the contact strips (Figure 10 4), the studs 6 and 7 are only in contact through the strip 8 and the spindle 11.

In order better to understand the operation of the apparatus it is only necessary to refer to the diagram given in Figure 5, and also Figure 5a 15 which shows the obverse side of switch 20 of Figure 5. This switch may be made of a plate of molded insulating material supporting the brass or metal contact pieces b—c—d—e—f—g—h—i.

An axle j is in electrical contact with the connecting or contact arm n is rotatable in the center of the plate and causes the contact pieces to take various connections.

The contact pieces h and i carry spring o and p, which latter are insulated from each other by an air space, but said contact pieces h and i may be connected by means of the key 22 which is made of brass or any suitable metal and placed between the springs o and p which exert pressure on the key so that it is consequently wedged and electrically interconnects said two contact pieces h and i. The latter contact i being connected to the wire 24 coming from the main control switch A and one of the wires from induction coil 23. The contact arm n makes connection between axle 30 j of switch 20 and the contact h to which is connected the wire 27 communicating with contact 7 of the main switch A. The switch 20 is fed by the conductor 21. If the key is introduced between the springs o and p, the current is sent 40 through the wire 24 and into the coil 23.

By manipulating the axle j, it is obvious that electric current may be supplied to the various lamps at the extreme right in Figure 5 by causing a contact arm (not shown) to engage any one of the corresponding lower contacts in known manner within the range of said arm.

Returning now to the mentioned diagram, 15 is the two pole dynamo represented schematically by the collector, the brushes, the inductors 17 and the poles 16 which are constituted by permanent magnets. 18 represents the circuit-closer, 19 is the battery which is joined by a conductor 26 to the contact stud 4 of the special switch A forming the object of the patent. 20 is the switch 50

controlling the lighting and ignition in the vehicle. This switch 20 receives the current through a connection 27 joined to the stud 7 of the switch A. The contact key 22 passes current 5 to the ignition coil 23 and to the inductors 17 of the dynamo through the strip 9 and the connections 24 and 25.

The circuit-closer 18 has a terminal joined to the stud 5 of the switch A by the connection 28. 10 A wire 29 joins the dynamo directly to the stud 6 of the switch A.

In the case of battery ignition the operation is as follows:

The contact strip of the switch A being in 15 the position X (battery) and the contact key 22 being placed in the switch 20, the inductors are under tension from the battery through the connections 26, 4, 8, 11, 27, 22, 24, and 25 and the contact strip 9. The dynamo operates with the 20 magnets 16 and the supplementary inductors 17. It then charges the battery 19 through the circuit-closer, the wire 26 and the contact strip 8 joining the contact studs 5 and 4 of the switch A. The equipment then functions normally.

25 Let us suppose that the battery is short-circuited or damaged.

We then pass to the position Y of the switch A. The strip 8, no longer being on the contact studs 4 and 5, then removes the battery 19 from 30 the circuit. The inductors 17 are also switched out, the strip 9 no longer being on the contact studs 3 and 2.

The contact strip 8 is then on the stud 6 and connects it to the stud 7. The dynamo is only 35 operating on the magnets 16. The current produced by the dynamo is thus passed to the switch 20, which can supply current to the lamps and to the ignition coil, the accumulator battery being out of circuit.

40 It is therefore seen that the switch A forming the object of the patent has well accomplished the function consisting of insulating the accumulator battery from the general circuit, of short-circuiting the automatic charging cut-out 45 and of suppressing the action of the inductors on the dynamo.

In Figure 6 a modification of the main switch is diagrammatically illustrated showing how 50 three possible positions may be assumed by the switching member for the purpose of avoiding overcharging of the battery. In the third position, the switch cuts out the inductors and the dynamo charges the battery, the magnets only 55 producing the flux necessary for the operation of the dynamo. For this purpose a contact stud 31 is interposed between the studs 5 and 6, this being joined to the stud 5. At the side of the stud 4 and opposite the stud 31 is located a 60 stud 32 joined to the stud 4.

In this position (position Z, for weak charging) the dynamo operates only on the magnets 16, the inductors being switched off by means of the strip 9. The studs 2 and 3 no longer being 65 in contact, the dynamo then charges the battery with a weaker intensity of charge. To recapitulate, the device involves a rotary shaft 11, electrically connected to a lower contact disk 14, rigid with a double contact plug 8 and another 70 double contact plug 9 from which said shaft 11 is electrically insulated.

If this switch is placed in the battery position, the dynamo or generator functions so that the magnets and inductors supply a field of 75 induction and the device functions normally, that

is to say that the generator supplies the battery by the intermediary of the switch.

If the switch is placed on the generator position, the inductors are cut from the generator and the battery is cut out of circuit with regard 5 to the principal current; the generator then works in such manner that the current arising in the armature rotating in the magnetic field created only by permanent magnets is immediately directed to the receiving apparatus, such 10 as, ignition coil, lights, signaling, instruments, etc.

The switch admits of an intermediate position 15 in which the inductors are cut out of circuit and the generator feeds the battery. In this case the magnetic field is furnished only by the permanent magnets, thus avoiding an excessive charging of the battery.

As is obvious the invention is not limited to 20 the sole methods for carrying out the invention given above solely by way of example; quite to the contrary it embraces all variations within the scope of the appended claims.

What I claim and desire to secure by Letters Patent of the United States is:—

1. In a charging, ignition and lighting system for a vehicle provided with a lighting generator having an armature, permanent field magnets and electrical field inductors, and internal combustion engine, an ignition and lighting circuit, a storage battery and an automatic charging switch connected to said lighting generator, the automatic charging switch and storage battery each having a ground connection and both the generator and storage battery being interconnected, means for cutting out said automatic charging switch, comprising an insulating plate provided with a plurality of distinct insulated contacts, and a rotary shaft, the first contact being connected to the storage battery 40 and a second correspondingly opposite contact being connected to said automatic charging switch, a pair of contact members upon said shaft insulated from each other, one of said contact members being in continuous electrical contact with said shaft, brush means connecting part of the generator armature output with the ground, means connecting said shaft to a third one of said contacts, which in turn connects with a portion of the ignition and lighting circuit of the system, another portion of the latter being grounded, means connecting a fourth one of said contacts with one portion of the main generator output, means also connecting a fifth one of said contacts with a portion of said ignition and lighting circuit, brush means interconnecting a portion of the generator armature output with the output of the field inductances, and means connecting a sixth one of said contacts with the electrical field inductances of said generator, which shaft in one rotated position retains one of the contact members thereon in contact with the first contact and with the second contact so as to connect said storage battery with said generator through said automatic charging switch, the shaft in the same position also retaining the other contact member upon the same simultaneously in contact with the fifth and sixth of said contacts, and which shaft in another rotated position retaining said contact members out of contact with said first, second, fifth and sixth contacts so as to cut out the storage battery and the inductances of the generator and retaining the third mentioned contact member in contact with the fourth contact 75

and thus connecting the output of the generator with the ignition and lighting circuit of the system for said vehicle while the generator is running with solely the permanent magnetic field of the permanent field magnets in action.

5 2. In a charging, ignition and lighting system for a vehicle provided with a lighting generator having an armature, permanent field magnets and electrical field inductors, an internal 10 combustion engine, an ignition and lighting circuit, a storage battery and an automatic charging switch connected to said lighting generator, both the generator and storage battery being interconnected, means for cutting out said automatic 15 charging switch, comprising an insulating plate provided with a plurality of distinct insulated contacts, and a rotary shaft, the first contact being connected to the storage battery and a second correspondingly opposite contact 20 being connected to said automatic charging switch, a pair of contact members upon said shaft insulated from each other, means connecting said shaft to a third one of said contacts, which in turn connects with the ignition and 25 lighting circuit of the system, means connect-

ing a fourth one of said contacts with a portion of said ignition and lighting circuit, means connecting a fifth one of said contacts with the electrical inductances of said generator, which shaft in one rotated position retains one of the 5 contact members thereon in contact with the first contact and with the second contact so as to connect said storage battery with said generator through said automatic charging switch, the shaft in the same position also retaining the 10 other contact member upon the same simultaneously in contact with the fourth and fifth of said contacts, and means upon said plate adapted to be engaged and contacted by one of the contact members upon said shaft in another rotated 15 position of the latter, connecting said generator with the ignition and lighting circuit for the vehicle while cutting out said automatic charging switch as well as the electrical inductances of the generator and the storage battery and feeding the ignition and lighting circuit with current generated in said generator while solely the 20 permanent field magnets are in action.

AUGUSTE SOULET. 25
